ington, N. J., a corporation of New Jersey

Application September 2, 1948, Serial No. 47,363
In Great Britain September 23, 1947

12 Claims. (Cl. 12—47)

1

This invention relates to trimming machines and is herein illustrated as embodied in a machine for breasting built up leather heels.

The present invention which is fully disclosed in the following description and claims consists in the novel features hereinafter described, reference being had to the accompanying drawings which show one embodiment of the invention selected for the purpose of illustration.

In the drawings,

Fig. 1 shows in perspective the illustrative heel breasting machine as viewed from the front and the right of said machine;

Fig. 2 is a front view, partly broken away and partly in section, of the machine;

Fig. 3 is a front view, partly broken away, showing portions of an operating head of the machine in the process of breasting a heel;

Fig. 4 is a view of the machine on line IV—IV of Fig. 2 showing in plan a heel supporting block and heel positioning mechanism associated therewith;

Fig. 5 is an enlarged side view showing a heel in the process of being breasted by the illustrative machine;

Fig. 6 is a side view of the heel supporting block and breast gage supporting mechanism as viewed on line VI—VI of Fig. 4;

Fig. 7 shows in front elevation portions of the heel supporting block and the heel positioning mechanism as viewed on line VII—VII of Fig. 4;

Fig. 8 is a view similar to Fig. 7 showing the heel positioning breast gages of the machine in raised positions to facilitate the removal from the block by the blower of a chip trimmed from the heel;

Figs. 9, 10 and 11 are illustrative views showing portions of breast gage operating mechanism during three different stages in the operation of the machine; and

Fig. 12 shows in front elevation, partly broken away and partly in section, portions of knife operating mechanism and mechanism for operating the chip ejecting blower of the machine.

The illustrative machine is described with reference to breasting an unattached built-up leather heel 20 (Figs. 2 to 6 inclusive) which is to be attached to a shoe (not shown) by the well-known "push-on" method practiced by the use of the machine disclosed in an application for United States Letters Patent Serial No. 573,026, filed January 16, 1945, in the names of Thomas B. Clarke and Arthur A. Rivington, which issued on September 6, 1949, as Patent No. 2,480,905. The heel 20 to be breasted is supported upon a table, sup-

2

port or block 22 with its top lift 24 (Figs. 5 and 6) in engagement with a flat upper face or surface 25 of the block, and is positioned widthwise and lengthwise on said face by side gages 26, 26a and breast gages 28 respectively which will be hereinafter described in detail. When the heel 20 has been positioned upon the face 25 of the block 22 the operator depresses a treadle 30 (Figs. 1 and 2) causing, through mechanism which will be described later, a cutting edge 32 of a knife 34 (Figs. 1, 2, 3 and 5) secured to a knife slide 36 (Figs. 1, 2 and 12) vertically slidable in a main frame 37 of the machine to engage an attaching face 38 (Figs. 4, 5 and 6) of the heel 20, resistance 10 against the knife being effective to cause the tripping of a one-revolution clutch 40 (Figs. 1 and 2) with the result that an operating rod 42 (Figs. 2, 3 and 12) is driven through a cycle further to depress the knife slide 36 to trim a chip 44 (Fig. 4) from the breast of the heel.

The length of the top lift 24 of the untrimmed heel 20 is approximately the same as that desired in the breasted heel, it being customary to shave from the breast of the top lift of said heel the chip 44, lateral margins of which are as thin as practicable. The breasts of upper lifts 46 of the unbreasted heel 20 sometimes project slightly forward of the breast of the top lift 24 as best shown in Fig. 5 but are commonly in substantial alignment with the breast of the top lift.

The heel supporting block 22 is provided with a pair of arcuate ribs 48 (Figs. 1 and 2) fitting slidably in arcuate guideways 50 formed in spaced upstanding flanges of a mount 52 which has a shank 54 (Fig. 1) fitting in a split boss portion 56 of the main frame 37 and which has a depending threaded portion 58 fitting in a bore 60 in the upper end of a column 62. The column 62 is supported upon a bearing 64 secured to the main frame 37 and has its lower end disposed in a notch 66 of the main frame. Since the shank 54 of the mount 52 fits in a bore of the boss portion 56 of the main frame 37 and the threaded portion 58 of said mount fits in the bore 60 of the column 62, it will be clear that said column does not swing on the bearing 64, the present machine being a change-over of a well-known machine which is used for breasting heels attached to shoes and in which the column swings to a slight extent for the purpose of presenting work to the machine.

Threaded onto the threaded portion 58 of the mount 52 is a hand nut 68 having a flat lower face which rests upon the upper end of the column 62. Rotation of the hand nut 68 after re-

leasing a handled binding screw 70 effects the raising or lowering of the mount 52. The binding screw 70 is used for clamping the split boss portion 56 of the main frame 37 to the shank 54 of the mount 52, a handled setscrew 72 threaded into the front upstanding flange of the mount 52 being used for binding the block 22 in its proper angular position upon the mount. The block 22 is initially set in its proper angular position upon the mount 52 and the mount in its proper height-wise position upon the column 62 by the use of the above-described mechanism, the knife 34 thereafter being properly adjusted upon and secured to its slide 36 by mechanism generally indicated by the reference numeral 73 so that the cutting edge 32 of the knife shall just engage the upper face 25 of the block at the lower end of travel of the knife.

The knife slide 36 reciprocates along guide-ways 74 (Figs. 2 and 12) of the main frame 37 and is constantly urged upward by a spring 76 (Fig. 12), upward movement of the knife slide being limited by the engagement of a flange 78 extending from the rear of said slide with a nut 80 adjustably secured to the upper end of the operating rod 42 which fits slidingly in a bore 82 of the flange and is pivoted at its lower end to a connecting rod 84 (Figs. 2, 3 and 12). The lower end of the rod 84 is pivotally connected to a crank 86 (Fig. 2) driven by a main drive shaft 88. The knife operating mechanism is substantially identical with that described in United States Letters Patent No. 1,117,627, granted November 17, 1914, on an application filed in the name of Arthur Bates, the only difference being that the knife of the present machine is operated through the treadle 30 whereas the knife of the machine disclosed in said Patent No. 1,117,627 is operated by a hand lever. The treadle 30 is mounted upon a pivot rod 90 (Figs. 1 and 2) and has operatively connected to it the lower end of a link 92, the upper end of which is pivoted to the central part of a floating lever 94. The left end of the floating lever 94 as viewed in Figs. 1 and 2 is operatively connected through a link 95 to the knife slide 36 and the right end of said lever is pivotally connected to a clutch control rod 96 which is constantly urged by a spring 98 to a raised position in a slot 100 of the main frame 37 and the lower end of which is pivotally connected to an operating rod 102 which corresponds to the operating lever 70 of the construction disclosed in said Patent No. 1,117,627 and is pinned to a rock shaft 104 carried by the main frame. The illustrative one-revolution clutch 40 is of the "roller" type disclosed in said Patent No. 1,117,627 and comprises a stop arm 106 which is also pinned to the rock shaft 104 and to which is secured a U-shaped spring 108. The rock shaft 104 has also secured to it an arm 110 to an outer end of which is attached a spring 112 for constantly urging, through mechanism described in detail in said Patent No. 1,117,627, the U-shaped spring 108 into a position to be engaged by a shoulder 114 of a member 116 of the clutch. When the treadle 30 is first depressed the floating lever 94 is moved counterclockwise as viewed in Figs. 1 and 2 about the upper end of the rod 96 which is then held in its raised position by the spring 98. When the knife 34 has been lowered into engagement with the heel 20 and meets resistance the spring 98 is compressed, continued depression of the treadle rod 92 causing the lowering of the clutch control rod 96 and through the above-described mechanism the withdrawal of the U-shaped spring 108

from engagement with the shoulder 114 of the clutch member 116 with the result that the drive shaft 88 is rotated through a complete revolution. The U-shaped spring 108 is thereafter swung into the path of the shoulder 114 of the clutch member 116 by mechanism disclosed in detail in said Patent No. 1,117,627 to stop movement of the drive shaft 88. The knife slide 36 is raised together with the operating rod 42 by the action of the spring 76 (Fig. 12) it being the practice for the operator to release the treadle 30 immediately after the clutch has been tripped.

The side gages 26, 26a for positioning the heel 20 width-wise upon the upper face 25 of the block 22 have opposing downwardly converging faces 118, 118a respectively constructed and arranged to be engaged by opposite sides of the top lift 24 of the heel. The side gages 26, 26a comprise rectangular base portions 120 (Figs. 4, 7 and 8) having internal threaded portions in driving relation with left and right hand threaded portions 122, 124 of a screw 126 which is rotatably mounted in a bore 128 (Fig. 4) of the block 22 and has a knurled head. When the screw 126 is rotated in the block 22 the gages 26, 26a move equal distances toward or away from each other.

The gages 28 which are engaged by the lateral margins of the breast of the top lift 24 of the heel 20 are normally in heel gaging positions adjacent to or in engagement with the face 25 of the block 22. A bevel 130 (Fig. 5) on the knife 34 tends slightly to slide the heel forward, that is, to the right as viewed in Figs. 2 and 5 as the knife trims material from the breast of the heel. It is desirable that the gages 28 remain in their gaging positions adjacent to the block 22 while the upper lifts 46 (Figs. 5 and 6) of the heel are being breasted to insure the formation of a smooth breasting cut, the heightwise elements of which are straight. It is desirable, however, that as the heel top lift 24 which rests upon the face 25 of the block 22 is being breasted, the gages 28 shall move away from the heel under pressure of the lower end of the chip 44 forced forward by the beveled face 130 of the knife 34. As will be hereinafter explained, the breast gages 28 are held in their operative positions adjacent to or in engagement with the face 25 of the block 22 by spring pressure sufficiently heavy to insure that when the lifts 46 of the heel are being breasted the breast gage shall remain in its gaging position, said breast gages being yieldable against the action of said spring pressure by the chip 44 which is being trimmed from the top lift and is thrust forwardly by the bevel 130 of the knife 34. With the foregoing considerations in view the breast gages 28 may be moved forward about a common axis 132 (Figs. 4 and 6) of fulcrum pins 134 against the action of a spring 136.

Moreover, it is desirable after the breast heel has been removed from the machine automatically to eject the chip 44 from the machine by forcing it over the right edge of the block 22 as viewed in Fig. 2 by a blast or jet of air directed across the face 25 of the block from a nozzle 140 (Figs. 1, 2, 3 and 4). It has been found, however, that if the breast gages 28 are left in their heel gaging positions adjacent to or against the face 25 of the block 22 they interfere with the removal of the chip 44 from said block. Accordingly after the heel 20 has been breasted the breast gages 28 are moved upward and if desirable slightly to the right as viewed in Fig. 7 to raised retracted positions shown in Fig. 8 spaced a substantial distance, for example about $\frac{1}{2}$ " away from the

upper face 25 of the block, said breast gages being temporarily held in their raised positions above the block to provide adequate space for the chip to pass uninterruptedly beneath them as it is ejected from the machine by said blast of air from the nozzle 140. By causing the breast gages 28 to move slightly forward with relation to the heel as they are raised to their retracted positions away from the block 22 there is little likelihood of the breast gages tipping over the chip as they are moved to their retracted positions.

The breast gages 28 are secured in recesses 142 (Figs. 4, 6, 7 and 8) of associated friction spools 144 by screws 146 threaded into said spools, the gages extending to the left (Figs. 3 and 7) over the right end of the block 22 and then downward (Figs. 3, 6 and 7) toward the block and inward (Figs. 4 and 6) toward each other, the construction and arrangement being such that when the gages are in their operative positions adjacent to or against the face 25 of the block 22 they are engaged by the lateral margins of the breast of the top lift 24 of the heel. The spools 144 have conical friction faces 148 (Figs. 4 and 6) which engage associated conical friction faces 150 of the L-shaped plates 152, 152a, shank portions of said spools fitting in recesses 154 formed in said plates. The conical faces 148 of the spools 144 are forced against the conical faces 150 of the L-shaped plates 152, 152a, by springs 156 interposed between said plates and collars 158 secured to the spools. The strength of the springs 156 and the character of the faces 148, 150 of the spools 144 and the L-shaped plates 152, 152a are such that the spools and accordingly the breast gages 28 maintain initially adjusted positions upon the plates.

Rotatably mounted on pivot pins 160 secured to the heel supporting block 22 are flanges 162, 164 of a U-shaped rocker or mount 166 which, through a link 168 pivotally connected to the flange 164, a lever 170 pivoted to the link and a spring 172 (Figs. 2 and 3), opposite ends of which are attached to the main frame 37 and to the lever 170, is constantly urged counterclockwise as viewed in Figs. 7 and 8 about an axis 174 (Figs. 4 and 6) of the pins 160 toward a stop 176 carried by the block 22. The axis 174 of the pins 160 is positioned directly below the heel engaging portion of the gage 28. The flanges 162, 164 of the U-shaped rocker 166 have depending lugs 178 into which are threaded the fulcrum studs 184, inner ends of which fit in conical openings 180 of flanges 182 of a carrier plate 184 into which is threaded a stop screw 186 which is held in its adjusted position in the carrier plate by a locknut 188 and may be considered as part of the carrier. The stop screw 186 is constantly urged against a cam surface 190 which is formed in the block 22 and extends upward and to the right as viewed in Figs. 7 and 8, by the spring 136, opposite ends of which are attached to the flange 162 of the U-shaped rocker 166 and to the carrier plate 184. Secured to and projecting from the carrier plate 184 is a screw 192 which extends through elongated slots 194, 196 of the L-shaped plates 152, 152a respectively and through a bore of an adjusting bar 198, said screw having threaded onto it a wing nut 200. Also threaded into the carrier plate 184 is a stud 202 which fits in the elongated slots 194, 196 of the L-shaped plates 152, 152a respectively. Formed in the adjusting bar 198 are slots 204 for receiving studs 206 carried by the plates 152, 152a respectively. When the wing nut 200

is clamped against the adjusting bar 198 the L-shaped plates 152, 152a are secured firmly to the carrier plate 184. In setting up the machine the breast gages 28 are moved equal distances toward or away from each other after loosening the wing nut 200, by turning the bar 198 in the proper direction upon the screw 192, the wing nut thereafter being screwed onto the screw into clamped relation with the bar to secure the plates 152, 152a to the carrier plate 184. The carrier plate 184 together with the various parts which are mounted upon said plate and support the breast gages 28 may be referred to as a carrier 208.

It will be apparent that when the U-shaped rocker 166 (Figs. 4, 6, 7 and 8) is swung counterclockwise from its position illustrated in Fig. 7 to its position shown in Fig. 8 about the common axis 174 of the pivot pins 160 the breast gages 28 which may be referred to collectively as a breast gage are moved to their raised positions spaced a substantial distance above the face 25 of the block 22. As the U-shaped rocker 166 swings counterclockwise as viewed in Fig. 7 the stop screw 186 of the carrier rides up the cam surface 190 and causes the carrier to rotate clockwise upon the rocker thereby compensating for the angular movement of the rocker and thus insuring that said gage 28 shall be raised at right angles to the face 25 of the block 22. If desirable the shape of the cam surface 190 may be varied so as to impart a component of movement forward of the heel to the gages 28 as said gages are moved to their raised positions, thereby insuring that the chip 44 shall not be pushed up or knocked over as the gages are raised.

During the breasting of the upper lifts 46 of the heel 20 the spring 136 is strong enough to retain the breast gages 28 in their gaging positions but as the knife 34 breasts the top lift 24 of the heel the breast gages 28 under pressure of the lower end of the chip 44 being severed are forced slightly to the right as viewed in Fig. 3 by the beveled face 130 of the knife 34 causing said gages to yield against the action of the spring 136 thereby relieving pressure against the knife and insuring against deflection of said knife from its rectilinear path.

As the knife 34 starts to rise after breasting the heel 20 the operator removes the heel from the face 25 of the block 22 leaving the chip 44 resting upon said block. During the first part of the upward movement of the knife 34 it is desirable to move the breast gages 28 to their raised positions shown in Fig. 4 in order that when a blast or jet of air is forced from the nozzle 140, against the chip 44 as the knife approaches the upward end of its movement, said chip may be removed without interference from the gages. In order to actuate at the proper times the breast gages 28 and a blower or ejector 212 which is connected by a hose 213 to the nozzle 146, said gages and blower are operatively connected to the operating rod 42 through mechanism herein-after described. Pivotally mounted in the main frame 37 is a shaft 214 to opposite ends of which are secured a lever 216 and a crank 218, the lever being operatively connected at its right end (Fig. 3) through a pin-and-slot connection 220 to the operating rod 42 and being pivotally connected at its left end to a rod 222 forming part of the mechanism for operating the blower 212. The arm 170, which is operatively connected to the link 168 for actuating the U-shaped rod 166, is secured to one end of a fulcrum pin 224 journaled in the main frame 37, the other end

of said pin being pinned to a depending latch arm 226. Positioned beneath the latch arm 226 and pivotally connected to the crank 218 is an actuator arm 228 which has a latch shoulder 230 and is constantly urged upward by a spring 232, upper and lower ends of said spring being attached to the main frame 37, and to the actuator arm. The crank 218 and the actuator arm 228 may be described as forming a toggle which is substantially straightened out as illustrated in Fig. 3 when the operating rod 42 and accordingly the knife 34 are at the lower ends of their strokes at which time the latch shoulder 230 is displaced to the left of a face 234 of the latch arm 226 and is also forced downward away from the latch arm by a collar 236 secured to a rod 238 actuated, as will be hereinafter explained, by the blower 212.

Associated with the blower 212 is trip mechanism 239 (Figs. 2 and 3) comprising a plunger 240 (Figs. 2, 3 and 12) which is vertically slideable in a bore 242 (Figs. 3 and 12) in the upper end of a cylinder 244 and is constantly urged by a spring 246 to an idle dash-line position (Fig. 3) in which the lower end of the plunger extends into the upper end of a bore 248 of the cylinder 244.

Pivoted upon a stud 250 fixed to a lug 252 secured to the cylinder 244 is a lever 254 into the rear end of which is threaded an adjustable screw 256 and to the forward end of which is pivoted the rod 238. The lower end of the rod 238 extends through an opening 258 in the actuator arm 228, the collar 236 on the rod being constructed and arranged to overlie a face 260 (Figs. 3 and 9) of the actuating arm. When the knife 34 is at the lower end of its breasting stroke a piston 262 slideable in the bore 248 of the cylinder 244 is at the upper end of said bore and has moved the plunger 240 upward against the action of the spring 246 causing the collar 236 of the rod 238 to move the actuating arm 228 counterclockwise about the crank 218 against the action of the spring 232. As the knife 34 moves upward to its raised starting position the piston 262 is moved downward in the air cylinder 244 by mechanism hereinafter described with the result that the collar 236 of the rod 238 is raised away from the actuating arm 228, said actuating arm under the action of the spring 232 moving clockwise against the latch arm 226 with its shoulder 230 arranged to the left (Fig. 9) of the face 234 of the latch arm. At the same time the crank 218 swings counterclockwise causing the breaking of the toggle and the actuator arm 228 to be drawn to the right thus moving the latch arm 226 counterclockwise and accordingly through the above-described mechanism the breast gages 28 upward to their positions shown in Fig. 8.

As the operating rod 42 is raised the lever 216 is swung counterclockwise (Fig. 12) causing the rod 222, a face 264 of which is then in engagement with a retaining pin 266 secured to the piston 262, to be moved downward. The rod 222 is normally urged to a position in which its face 264 overlies the retaining pin 266 by a leaf spring 268 secured to the piston 262 and as said rod is lowered the piston is lowered in the bore 248 of the cylinder 244 against the action of a coil spring 272, upper and lower ends of which engage the piston and the cylinder respectively. Although as above explained the breast gages 28 are moved to their raised positions illustrated in Fig. 8 away from the block 22 during the first

part of the retractive movement of the knife 34 it is desirable to delay the blast or jet of chip ejecting air through the nozzle 140 until the knife has almost reached the upper end of its stroke thereby allowing the operator ample time in which manually to remove the breast heel from the block 22 before ejecting said chip. In order to swing the rod 222 away from the retaining pin 266 near the upper end of the stroke of the knife 34 the operating rod 42 has an extension 274 (Figs. 3 and 12) to which is secured a collar 276 (Fig. 12). Pivotally mounted upon a pin 278 secured to the main frame 37 is a bell crank lever 280, an upper arm of which has threaded into it a screw 282 and a lower arm of which is pivotally connected to a link 284 supported in a horizontal position by a pin 286 carried by the main frame 37 and extending through an elongated slot 288 in the link. The link 284 is also provided with a bore 290 through which passes the rod 222, said rod passing down through the bore as the operating rod 42 is raised. When the knife 34 and accordingly the operating rod 42 have almost reached their upper limits of travel the collar 276 engages the screw 282 causing the bell crank lever 280 to swing counterclockwise and withdraw the face 264 of the rod 222 from the retaining pin 266 against the action of the leaf spring 268 thus permitting the piston 262 to move to its elevated position in the cylinder 244 under the action of the coil spring 272 and accordingly causing air in the bore 248 of the cylinder 244 to be ejected under pressure through the nozzle 140 to blow the chip 44 remaining on the block 42 from said block.

In breasting heels 20 by the use of the above-illustrated machine the operator places the heel, top lift 24 down, upon the face 25 of the block 42 between the side gages 26, 26a then initially adjusted and slides the heel to the right as viewed in Fig. 2 until the lateral margins of the breast of the top lift of the heel are in engagement with the breast gages 28 respectively, the side gages being finally adjusted to position the heel widthwise on said face. When the heel 20 has been positioned upon the block 22 the operator depresses the treadle 30 causing the knife slide 36 to be lowered against action of the spring 76 (Fig. 12) until the knife 34 is resisted substantially by the heel. As downward movement of the treadle 30 continues the clutch control rod 96 is lowered against the action of the spring 98 with the result that the one-revolution clutch 40 is tripped, the operating rod 42 being actuated to lower the knife slide 36 to effect the breasting of the heel. The treadle 30 is immediately released by the operator after the one-revolution clutch 40 has been tripped, the knife slide 36 and the operating rod 42 being raised together to their starting positions.

As material is removed from the breast of the top lift 24 of the heel the breast gages 28 yield slightly forward away from the heel, against the action of the spring 136, under pressure of the chip 44 thrust forward by the action of the bevel face 130 of the knife. As the knife 34 starts its upward movement away from the block 22 the breast gages 28 are raised from their gaging positions illustrated in Fig. 7 adjacent to the block to their positions illustrated in Fig. 8 leaving between them and the face 25 of the block an adequate space to facilitate removal of the chip 44 from the block.

During the retraction of the knife 34 the operator manually removes the breast heel from

the machine and just before said knife reaches the upper end of its stroke a jet of air is ejected from the nozzle 140 to blow the chip 44 then on the block 22 from the right edge of the block as viewed in Fig. 8 into a container (not shown).

Having thus described the invention, what I claim as new and desire to secure by Letters Patent of the United States is:

1. In a trimming machine a support for a shoe part, means comprising a gage for positioning said shoe part on the support, a movable knife for trimming a chip from said shoe part, ejecting means for removing said chip from the support, mechanism for moving said gage from an operative gaging position adjacent to said support to a position spaced a substantial distance from said support to facilitate removal of the chip from the support by said ejecting means, and means movable in response to movement of the knife for operating said mechanism to move the gage away from the support and for thereafter operating said ejecting means to effect removal of the chip from the support.

2. In a trimming machine, a support for a shoe part, means comprising a gage for positioning the shoe part on the support, means comprising a stop for positioning the gage in an operative gaging position adjacent to the support, a reciprocative knife movable toward the support to trim a chip from said shoe part, mechanism comprising resilient means for constantly urging the gage toward its gaging position, an actuator movable in response to movement of the knife, means for coupling the actuator to said mechanism during movement of the knife away from the support to move said gage a substantial distance away from the support, an ejector for removing the chip from the support, and means responsive to movement of the ejector for uncoupling the actuator from said mechanism when the chip has been removed from the support to cause the gage to be moved back to its gaging position adjacent to the support in response to movement of said resilient means.

3. In a trimming machine a support for a shoe part, means comprising a gage for positioning the shoe part on the support, means comprising a stop for positioning the gage in an operative gaging position adjacent to the support, a reciprocative knife movable toward the support to trim a chip from said shoe part, mechanism comprising a spring for constantly urging the gage toward its gaging position, an actuator operatively connected to the knife, means for coupling the actuator to said mechanism during movement of the knife away from the support to move said gage a substantial distance away from the support and away from the chip trimmed from said shoe part and left on said support, a blower for removing the chip from the support, and means responsive to movement of the blower for uncoupling the actuator from said mechanism when the chip has been removed from the support to cause the gage to be moved back to its gaging position adjacent to the support in response to movement of said spring.

4. In a trimming machine, a support for a shoe part, means comprising a gage for positioning the shoe part on the support, mechanism comprising resilient means for moving the gage to and holding it in an operative shoe part gaging position adjacent to the support, an actuator, a spring for constantly urging the actuator into a coupling position with relation to said mechanism, a reciprocative knife movable toward the support

to trim a chip from said shoe support, a blower for ejecting said chip from the support, means movable in response to movement of the knife away from said support for first causing said mechanism to move the gage against the action of said resilient means to an inoperative position spaced a substantial distance from the support and for thereafter effecting operation of the blower to eject said chip from the support, and means movable in response to operation of the blower for disengaging, against the action of said spring, the actuator from said mechanism when the chip has been removed from the support to cause the gage to be moved under the action of said resilient means back to its gaging position adjacent to the support.

5. In a heel breasting machine, a support for a heel, means for positioning the heel upon the support, said means comprising a gage which is movable to a gaging position adjacent to said support and is constructed and arranged to be engaged by the breast of the heel, a reciprocative knife movable toward the support to trim a chip from the breast of the heel and movable to a retracted idle position away from said support, and means responsive to movement of the knife to its retracted position for raising the gage a substantial distance from the support to facilitate removal of the chip from said support.

6. In a heel breasting machine, a block having a surface for supporting a heel, means for positioning the heel widthwise upon said surface, a gage which is positioned adjacent to said surface and is constructed and arranged to be engaged by the lateral margins of the breast of the heel to position said heel lengthwise on said surface, a knife which is movable toward said surface of the block to trim a chip from the breast of the heel and which is movable to a retracted position away from said surface, and means operative in timed relation with the knife for raising, during retraction of the knife, the gage a substantial distance away from said surface to facilitate removal of the chip from said surface.

7. In a heel breasting machine, a support for a heel, means comprising a breast gage for positioning the heel upon the support, and a knife which is movable toward the support to trim a chip from the breast of the heel and which is movable away from the support to a retracted starting position, said breast gage being movable simultaneously about spaced parallel axes in response to retractive movement of the knife to move the gage a substantial distance away from said support in order to facilitate removal of the chip from the support.

8. In a heel breasting machine, a support for a heel, means for positioning the heel widthwise on the support, a gage which is positioned adjacent to said support and is constructed and arranged to be engaged by the breast of a top lift of the heel and not by other lifts of the heel to position said heel lengthwise on said support, a reciprocative knife movable toward the support to cut a chip from the breast of the heel, and mechanism which is constructed and arranged to hold the gage stationary with relation to the support when said other lifts of the heel are being breasted but which is yieldable under pressure of the chip formed between the knife and the gage when the top lift of the heel is being breasted.

9. In a trimming machine, a support for a built up heel having a top lift, means for positioning the heel upon the support, said means comprising

11

ing a gage constructed and arranged to be engaged by the lateral margins of the breast of said top lift, a reciprocative knife movable toward and against the support to trim a chip from the breast of the heel, an ejector for removing the chip from the support, a carrier for the gage, a member which is movable with relation to the support and upon which the carrier is pivotally mounted, a cam, a cam follower mounted upon the carrier, a spring for constantly urging said follower against the cam, and means for moving said member to cause the carrier to move with said member and to cause the carrier simultaneously therewith to swing on said member by reason of movement of the cam follower along said cam thereby moving the gage a substantial distance from the support to facilitate the ejection of the chip from the support.

10. In a heel breasting machine, a support for a built up heel which has a top lift, means for positioning the heel upon the support, a breasting knife, mechanism for moving the breasting knife toward and against the support to trim a chip from the heel and for moving the knife to a retracted position away from the support, an ejector for removing the chip from the support, said heel positioning means comprising a pair of gages which are normally positioned adjacent to the support and are constructed and arranged to be engaged by the lateral breast margins of the top lift of the heel, a member mounted for pivotal movement about an axis extending widthwise of the heel and arranged directly below heel engaging portions of said gages, a carrier for said gages, said carrier being pivotally mounted upon said member for movement about an axis which is parallel to the first-named axis and is arranged below and forward of the heel, a cam, a cam follower fixed to the carrier, a spring which constantly urges said cam follower against the cam and which enables the carrier and accordingly the gages to move forward yieldingly with relation to said member when the top lift of the heel is being breasted, and means movable in

12

response to movement of the knife for actuating said member to cause the gages to be moved a substantial distance away from the support to facilitate ejection of the chip from said support.

5. 11. In a heel breasting machine, a support for a heel, means for positioning the heel widthwise upon the support, gages constructed and arranged to be engaged by the breast of the heel for positioning said heel lengthwise upon the support, a reciprocative breasting knife movable toward the support to trim a chip from the breast of the heel and back to a retracted position, means for operating the knife, a carrier for said gages, means for moving the carrier from an active position in which the gages are positioned adjacent to the support to a retracted position in which the gages are moved a substantial distance away from the support and are moved away from the chip upon the support, a blower for directing a jet of air against the chip upon the support, and mechanism operative in timed relation with the knife for actuating said means to move the carrier to its retracted position for facilitating removal of the chip from the support and for thereafter operating the blower to remove said chip from the support.

20. 12. In a heel breasting machine, a support for a heel, means comprising a pair of breast gages for positioning the heel upon the support, a reciprocative knife movable toward the support to trim a chip from the breast of the heel, an ejector for removing the chip from the support, a mount, a carrier for said gages pivotally supported upon the mount, a cam, a spring for forcing the carrier against the cam to control the angular movement of the carrier upon the mount, and means movable in timed relation with the knife for operating the mount to move the gage away from the support and simultaneously therewith to swing the carriage and accordingly the gages upon the mount.
